CLAIM

The ornamental design for a lunch box as shown and described.

DESCRIPTION

FIG. 1 is a front elevational view of a first embodiment of a lunch box showing my new design;

FIG. 2 is a rear elevational view of FIG. 1;

FIG. 3 is a left side view of FIG. 1;

FIG. 4 is a right side view of FIG. 1;

FIG. 5 is a top plan view of FIG. 1;

FIG. 6 is a bottom plan view of FIG. 1;

FIG. 7 is a bottom, front and left side perspective view of FIG. 1;

FIG. 8 is a top, rear and right side perspective view of FIG. 1;

FIG. 9 is a bottom, front and right side perspective view of FIG. 1 shown with the right side container removed;

FIG. 10 is a bottom, front and right side perspective view of FIG. 1 shown in an open configuration with the right side container removed;

FIG. 11 is a front elevational view of a second embodiment of the lunch box;

FIG. 12 is a rear elevational view of FIG. 11;

FIG. 13 is a left side view of FIG. 11;

FIG. 14 is a right side view of FIG. 11;

FIG. 15 is a top plan view of FIG. 11;

FIG. 16 is a bottom plan view of FIG. 11;

FIG. 17 is a bottom, front and left side perspective view of FIG. 11;

FIG. 18 is a top, rear and right side perspective view of FIG. 11;

FIG. 19 is a bottom, front and right side perspective view of FIG. 11 shown with the right side container removed; and, FIG. 20 is a bottom, front and right side perspective view of FIG. 11 shown in an open configuration with the right side container removed.

The broken lines in the drawings illustrate portions of the lunch box which form no part of the claimed design.
